(57) **CLAIM**

The ornamental design for a rider detection sensor for electric vehicle, as shown and described.

DESCRIPTION

FIG. 1 is a perspective view of the new design for a rider detection sensor for electric vehicle;

FIG. 2 is a front view thereof;

FIG. 3 is a rear view thereof;

FIG. 4 is a left side view thereof, the right side view being a mirror image thereof;

FIG. 5 is a top view thereof; and,

FIG. 6 is a bottom view thereof.

The dash-dash broken lines illustrate portions of the article that form no part of the claimed design.

The dash-dot broken lines define the bounds of the claimed design and form no part thereof.

1 Claim, 4 Drawing Sheets

FIG. 1

FIG. 2

FIG. 3

FIG. 5

FIG. 6

FIG. 4
